UNITED STATES PATENT OFFICE.

WALTER P. OSGOOD, OF MALDEN, MASSACHUSETTS, ASSIGNOR TO BOSTON MACHINE WORKS COMPANY, OF LYNN, MASSACHUSETTS, A CORPORATION OF MASSACHUSETTS.

TAPING MACHINE.

Application filed January 12, 1922. Serial No. 528,727.

To all whom it may concern:

Be it known that I, WALTER P. OSGOOD, a citizen of the United States, and resident of Malden, county of Middlesex, State of Massachusetts, have invented an Improvement in Taping Machines, of which the following description, in connection with the accompanying drawing, is a specification, like characters on the drawing representing like parts.

This invention relates to a machine for applying tape to sheet material. A machine for this purpose is capable of a wide use wherever it is desired to apply a strip 15 of tape to sheet material, but is specially useful in the shoe industry for applying a strip of tape to the different parts of the upper of a shoe.

In the manufacture of shoes it is a common practice to thus apply tape to the shoe uppers, sometimes for the purpose of reinforcing the edge of quarters, vamps, etc., and sometimes for the purpose of covering the lining directly beneath the perforations 25 formed in the upper for ornamental purposes to prevent the lining from showing through the perforations. In the latter case the tape is applied to the inside of the upper so as to cover the perforations, the tape 30 usually being of the same color as the upper.

One of the objects of my invention is to provide a taping machine which is constructed so that the tape may be applied as readily on a curve as in a straight line.

Another object of the invention is to provide an improved taping machine in which the tape may be readily applied in a reverse curve as well as along a line which curves in one direction only.

Another feature of my invention relates to a novel taping machine by which when the tape is applied along a curved line the portion of the tape on the inner edge of the curve will be gathered and flattened 45 against the work.

Still another feature of the invention relates to a novel means for delivering the tape to the tape-applying mechanism free from tension so that as the tape is applied 50 to the work it is subjected only to the tension given to it by the tape-applying means.

Still another object of the invention is to provide an improved taping machine which is adapted to apply the tape either by a

so-called "cold process" or by a so-called 55 "hot process." In the cold process the tape is drawn through a cement container provided with a suitable cement so that when the tape is delivered to the work it will be cement-coated and will thus be caused to adhere to the work. In the hot process the tape has been previously provided on one face with a cementitious coating which is of such a nature that it is normally hard but will become tacky when heated. In applying this tape according to the hot process 60 the tape is heated as it is applied and the heat softens the cementitious coating on the tape sufficiently to cause the tape to adhere to the work.

Still another object of the invention is to provide a novel machine of this type in which the work is fed forward by the movement of the presser member. For this purpose the presser element has an oscillating 70 motion in addition to its movement toward and from the work, these combined movements operating to bring the presser member against the work to press the tape thereto and then causing the member to have a 75 rocking movement as well as a forward movement which results in feeding the work and at the same time pressing the tape to the work with a rocking movement.

Still other objects of my invention are 80 to improve generally taping machines in particulars which will be more fully herein-after set forth.

In order to give an understanding of the invention I have illustrated in the drawings a selected embodiment thereof which will now be described after which the novel features will be pointed out in the appended 85 claims.

Fig. 1 is a front view of a taping machine 90 embodying my invention.

Fig. 2 is a similar view showing the parts in a different position.

Fig. 3 is an edge view of the pivot fingers.

Fig. 4 is a side view of said fingers.

Fig. 5 is a section on the line 5—5, Fig. 2.

Fig. 6 is a side view of the head portion 100 of my improved taping machine.

Fig. 7 is a perspective view showing the operation of laying the tape along a curved 105 line.

Figs. 8 and 9 are views of the tape feeding mechanism showing the parts in different

positions from what is illustrated in Figs. 1 and 2.

Fig. 10 is a perspective view of the work guide.

5 Fig. 11 is a section on the line 11—11, Fig. 6.

As stated above this machine is adapted to apply an adhesive-coated tape or strip to sheet material. For instance in Fig. 7

10 I have shown at 1 a piece of sheet material to which the tape strip 2 is applied, said strip having on its under face a coating of adhesive material so as to cause it to adhere to the work 1 when it is pressed there-
15 against. In said Fig. 7 the work 1 is shown as provided with a row of perforations 3 and the tape strip 2 is applied to the work so as to cover these perforations. This tape strip, however, might be applied to the edge
20 or any other portion of the work for reinforcing it.

The applying of the tape strip to sheet material to cover perforations is frequently resorted to in the manufacture of shoes
25 where the shoe upper is formed with rows of perforations for ornamental purposes and in such case it is desirable to cover the lining so that the latter will not show through the perforations after the shoe is completed.

30 For this purpose the tape strip 2 is applied to the inner face of the upper along the line of perforations thereby preventing the lining from being visible through the perforations.

35 The taping machine herein shown comprises a work support preferably in the form of a roll, over which the sheet material is fed, means for laying a tape strip on the sheet material as it is fed, a hammer
40 or presser member to press the tape against the sheet material and to feed the latter, and means for drawing the tape from a source of supply and delivering it free from tension to the tape-applying means.

45 This hammer or presser element has a movement toward and from the roll and it also has an oscillating movement which serves to feed the work forward and also to give the presser member a rolling contact
50 with the tape during the pressing operation.

The operative parts of the machine are carried by a suitable frame 4 which may have any desirable shape but will preferably be a shape so that it can be placed on a bench or table. The work-support, which as stated above is preferably in the form of a roll, is shown at 5 as mounted for rotation upon a shaft 6 carried by a slide 7 supported in a suitable base 8, the slide being acted upon by a spring 9 so that the work support is yieldingly supported. The tape strip 2 is delivered to the work 1 as it passes over the roll 5 through a tape-guiding device herein shown as a curved
65 guiding member 10 over which the tape

passes and a tension foot 11 resting on the tape and holding it against the guiding member 10 in a manner to apply a substantially uniform tension thereto. Said guiding member is shown as having ears 70 12 at its sides between which the tape passes and which retains the tape in its proper path. The tape is thus fed between the tension foot 11 and the guiding member 10 and is delivered to the work from these 75 parts. The tension foot 11 is yieldingly held against the tape as will be presently described. The tape is pressed against the work thereby to cause it to adhere thereto by means of a presser member 13, which is 80 in the form of a block having a convexly curved face 14, the curvature of which is slightly greater than that of the roll 5.

This presser member has a reciprocating movement toward and from the work and 85 also has an oscillating movement, the construction being such that the face 14 of the presser member has an advance rocking movement on the tape while it is in contact therewith, such rocking movement effectively pressing the tape against the work and also feeding the work and tape forwardly. Said member is, therefore, a combined presser and feed member.

The operative parts of the machine are 90 actuated from a driving shaft 15 journaled in the frame 4 and actuated from any suitable source of power. The presser member 13 is carried by an oscillating head 16, the latter having an extension 17 thereon provided with a portion 18 that encircles an eccentric 19 fast on the shaft 15. This head 16 oscillates about a stud 20 fast in the frame 4. The head 16 is shown as provided with a vertical slot 21 in which is 100 received a block 22 that is pivoted to the stud 20. This slot construction allows the head 16 to rise and fall with the movement of the eccentric 19 and the stud 20 furnishes the center about which it oscillates. The presser member 13 will thus have an oscillatory movement in an elliptical orbit and as the shaft rotates in the direction of the arrow Figs. 1 and 2 it will be seen that when the eccentric is passing 110 over the lower center the presser member 13 will be in contact with the tape and will be moving to the left Figs. 1 and 2 thus giving a feeding movement, while when the eccentric is passing over the upper center the 120 presser member will be elevated from the work and will be moving towards the right Figs. 1 and 2.

The curved face 14 of the presser member will thus have a rocking advance movement 125 while it is in engagement with the tape and this movement serves not only to press the tape against the work for a considerable length but also feeds the work forward. The extent of each feeding movement is, 130

however, less than the length of tape over which the face 14 rocks at each rocking movement, and, therefore, there will be a more or less overlapping action between successive rocking movements so that any part of the tape is subjected to two pressing operations.

The tape 2 is drawn from a source of supply, not shown, and then passes through a tape pull-off mechanism which withdraws the tape from the source of supply and delivers it to the tape-applying device, and from the pull-off mechanism the tape passes over a pulley or roll 23 pivoted at 24 on an arm 25 extending from the frame 4, and from this roll the tape passes to a curved tape-guiding member 26 which leads it to the delivery guide 10.

The tension foot 11 is shown as carried on the lower end of an arm 260 pivoted to a pin 27 carried in a forked support 28 that is secured to a boss 29 formed on the frame. For this purpose the support 28 is provided with a stem 30 which extends through the boss and said stem is held in adjusted position by a set screw 31. The tension foot has integral therewith a finger piece 32 which is acted upon by a spring 33 that yieldingly holds the tension foot against the tape. When the finger piece 32 is depressed the tension foot is elevated from the work.

The tape pull-off mechanism is constructed to positively draw the tape intermittent-ly from a source of supply and then to deliver the tape so drawn to the roll 23. The tape extends from the source of supply around the guide pins 34, 35 fast in a yoke member 36 secured to the frame 4, thence passes over a reciprocating pull-off stud 37 and thence passes over fixed guide pins 38, 39 also carried by the yoke 36 and thence passes to the direction roll 23. The pull-off stud 37 is secured to the portion 17 of the head and therefore has a rising and falling movement. During the rising movement it draws a loop of tape upwardly between the guide studs 35, 38 thus pulling tape from the source of supply, and during its downward movement it gives up the tape thus pulled off from the source of supply and a take up arm 40 acts on the tape to deliver the slack to the roll 23. This take up arm is shown as pivoted on the stud 37 and it is provided at its end with a stud 41 to act on the tape between the stud 39 and the roll 33. Said take up arm is actuated at proper times by a cam 42 fast on the shaft 15 and it is held against the cam by a return spring 43. The cam operates to give the take up arm repeated downward swinging movements into the position shown in Fig. 8.

In order to better control the feeding movement of the tape I have provided a gripping device which co-operates with the

stud 38 to grip the tape while the pull-off stud 37 is drawing out a loop 44 of tape between the studs 35, 38 and which co-operates with the stud 35 while the pull-off stud is moving downwardly, so as to insure that the take up arm will advance the slack in the loop 44 to the roll 23. This gripping device comprises two gripping members 45, 46 pivoted to the block 22 at 47 and 48 respectively. Each gripping device is provided with a curved serrated gripping face 49 and a spring 50 is placed between them which tends to separate them from each other. The block 22 carries stop screws 51 which limit the separating movement of the gripping members.

When the eccentric is passing over the low center into the position shown in Fig. 2 the oscillating movement of the block 22 will carry the gripping member 46 against the tape that passes over the stud 38 thereby gripping the tape at this point. The rising movement of the head 16 and pull-off pin 37 will elongate the loop 44 of tape and because the tape is gripped against the pin 38 the amount of tape necessary for elongating the loop will be drawn from the source of supply. When the eccentric passes over the top center as shown in Fig. 9 then the head 16 is swung to bring the gripping member 45 against the tape passing over the stud 35 and as the pull-off pin 37 moves downwardly to give up slack in the loop 44 the cam 42 acts on the take up arm 40 and draws this slack over the pin 39 to the roll 23.

The length of tape between the roll 23 and the approach guide 10 is, therefore, relatively free from tension, and as the tape is fed to the work from the guide 10 the tension foot 11 applies the requisite light tension thereto which is desirable to properly attach the tape to the work.

In addition to the above features my invention also contemplates a construction which facilitates the applying of the tape along a curved line. This is done by means which takes care of the fullness on the inside edge of the tape on the curve, either by flattening such fullness or by permitting it to form into plaits or folds which are pressed against the work so that they are hardly visible.

The device is also constructed so that the tape may be laid on a line which curves in either direction and this makes it possible to apply the tape rapidly along any edge contour or along any desired line without the necessity of stopping the machine in passing around corners to adjust the tape for the curve. In my invention the tape is automatically adjusted to fit the curve as the work is fed. This is illustrated in Fig. 7 wherein the line of perforations 3 which is to be covered by the tape 2 is formed on a curve. In feeding work of this type through

the machine the operator will manipulate the work so that the curved line of perforations will be fed beneath the tape-applying means. My improved mechanism is constructed so that at each forward step of the work a hump or loop 52 is formed in the tape on the inside of the curve immediately in front of the tension foot, and when the presser member 13 acts on the humped tape, 10 the hump or loop will be either flattened out or will be folded over against the body of the tape, as shown at 53 in Fig. 17, depending upon the character of the tape. If the tape is a light, very flexible tape, it will be 15 flattened out but if the tape is thicker and stiffer it will probably be formed into the fold or plait. The tape will thus be laid without stretching the edge on the outside of the curve and by merely gathering the tape 20 on the inside edge.

This result is secured by the employment of a pair of pivot fingers 54 which are pivotally mounted on the stud 27 and which are supported on the work at the marginal 25 portions of the tape in front of the tension foot. These fingers are acted upon by springs 55 which yieldingly hold them against the work and the ends of the fingers operate in slots formed in the presser 30 member 13 so that the fingers are engaging the work at the point where the presser member operates thereon. So long as the tape is being laid along a straight line it will be fed under the fingers and they will 35 simply act to prevent retrograde movement of the tape or work.

During the operation of laying the tape along a curve such as shown in Fig. 7, the work will be fed forward one step while it 40 is acted upon by the presser member 13, and when the presser member is raised from the work then the operator turns or swerves the work more or less depending on the sharpness of the curve. During this turning 45 movement of the work it will pivot on the finger 54 at the outer edge of the curve and the tape between the fingers 54 and the tension foot 11 will be formed into a hump or loop, as shown at 52, Fig. 7. The hump 50 or loop thus made at the inner edge of the curve has a conical form developing from the outer edge of the curve. When the presser member 13 is brought down against the work it flattens out this hump 52 either 55 with or without forming a fold or plait 53 depending upon the character of the tape and the sharpness of the curve. When the presser member 13 is again raised then the work will again be turned or swerved 60 slightly on the finger 54 on the outside of the tape as a pivot due to the pressure of the operator's hand, and another hump will be formed between the fingers and the tension foot, said hump being pressed down or 65 flattened out by the presser member at its

next descent. This operation is repeated clear around the curve and is as perfect on a sharp curve as on a gradual one, the only difference being that on a sharp curve the plaits will be wider than on a gradual curve. 70 If the curve is in the reverse direction or away from the operator, then the work will pivot on the pivot finger 54 nearest the observer, but otherwise the operations will be 75 as above described.

Where the curve is a very abrupt one it is sometimes desirable to relieve the pivot finger 54 on the inside of the curve of its spring pressure and I have provided for this herein by means of a cam member 80 56 which is fast on the stud 27, the latter being provided with a finger piece 57 by which it may be turned. This shaft has two cams 56 thereon, one for acting on each of the springs 55 and said springs are 85 formed with the wing portions 58 to be engaged by the cams. The high points of the two cams 56 are situated 90° apart so that when the shaft 27 is turned in one direction one spring 55 will be rendered inactive and when the shaft is turned through 90° the other spring will be rendered inactive. The shaft 27 may also be turned so that neither cam will be operative and, therefore, both springs will be active. During the laying of tape along a straight line the shaft 27 is situated so that both springs will be effective but when the tape is being laid on a sharp or abrupt curve then the shaft 27 will be turned to render one or 100 the other of the fingers 54 inoperative depending on the direction of the curve.

It will be noted that the face of the hammer or presser member 13 has a considerable extent longitudinally of the tape. In 105 fact the extent of this face is more than the distance which the tape is fed at each step so that each part of the tape will be acted on a plurality of times by the hammer or presser member. The advantage of this is 110 to insure that the tape will be firmly pressed against and caused to adhere to the work 1.

As the face 14 moves forwardly the work is fed and a new length of unattached tape 115 is fed into the space in advance of the tension foot to be applied to the work upon the next downward movement of the presser member 13 so that the feeding movement of the presser member operates not only to 120 feed the work but to draw tape through the tension foot.

Where the tape is to be laid adjacent the edge of the work it may be desirable to employ an edge guide by which the work may 125 be guided. I have herein shown an edge guide in the form of a guide member 99 to engage the edge of the work as shown in Fig. 6. This guide member 99 is adjustably carried on an arm 98 having a hub 97 which 130

is mounted on a stud 96. The purpose of thus mounting the guide is to permit it to be moved into and out of operative position.

When it is desired to use the guide it is thrown into the position shown in Fig. 6, but when it is not desired to use said guide it can be swung down.

This guide member is yieldingly held in its operative position by means of a tooth 10 or projection 94 carried by the frame entering a notch or projection 95 formed in the hub 97, a spring 93 serving to hold the tooth yieldingly in the notch. The notch can be readily disengaged from the tooth, 15 however, when it is desired to swing the guide into its inoperative position.

I claim.

1. In a machine for applying tape to sheet material, the combination with a work 20 support over which the work is fed, of tape-applying means to lay on the work as it is fed a continuous length of tape extending in the direction in which the work is fed, and a pull-off device operating while the 25 tape is being laid to draw tape from the source of supply and deliver it free of tension to the tape-applying means.

2. In a machine for applying tape to sheet material, the combination with a work 30 support over which the work is fed, of tape-applying means to lay on the work as it is fed a continuous length of tape extending in the direction in which the work is fed, and an intermittently-acting pull-off device 35 operating while the tape is being laid to draw tape intermittently from a source of supply and deliver it free of tension to the tape-applying means.

3. In a machine of the class described, 40 the combination with a work support over which the work is fed, of tape-applying means operating with a step-by-step movement to lay on the work as it is fed a continuous length of tape extending in the 45 direction in which the work is fed, and an intermittently-acting pull-off device acting on the tape before it is delivered to the tape-applying means and during the operation of applying the tape to the work to draw 50 tape from a source of supply and then deliver it free of tension to the tape-applying means.

4. In a machine of the class described, the combination with a work support free to 55 revolve and over which the work is fed, of tape-applying means to lay tape on the work as it is fed, a pull-off device operating while the tape is being applied to the work to draw tape from a source of supply and 60 deliver it free of tension to the tape-applying means, said pull-off device comprising a member having to-and-fro movement, and means to actuate it to cause it to act intermittently on the tape.

5. In a machine of the class described, the

combination with a work support over which work is fed, of tape-applying means to lay tape on the work as it is fed, a pull-off stud over which the tape passes, means to give said stud a to-and-fro movement to 70 cause it to draw off intermittently lengths of tape from a source of supply, and a take-up lever to act on the tape when released by the stud and deliver it to the tape-applying means. 75

6. In a machine of the class described, the combination with a work support, of a tape-guiding member to deliver tape in a continuous length to the work as it is fed over the work support, a presser member acting 80 intermittently on the tape to press it against the work and to feed the work forward, and a pull-off device acting on the tape before it is delivered to the presser member and operating during the continuing operation of the machine in timed relation with 85 said presser member to draw off intermittently lengths of tape from a source of supply and deliver said tape to the guide free of tension. 90

7. In a device of the class described, the combination with a work support over which work is fed, of tape-guiding means to deliver tape to the work, a movable head, a presser member carried thereby to press 95 the tape against the work and a pull-off device actuated by the movement of said head and operating while the tape is being applied to the work to draw tape from a source of supply and deliver it to the tape guide. 100

8. In a device of the class described, the combination with a work support over which the work is fed, of means to deliver tape to the work, a movable head, a presser member carried thereby and acting intermittently on the tape to press it against the work, and a pull-off stud also carried by the head and operating while the tape is being applied to the work to draw off intermittently lengths of tape from a source of supply. 110

9. In a device of the class described, the combination with a work support over which the work is fed, of means to deliver tape to the work, a movable head, a presser member carried thereby and acting intermittently on the tape to press it against the work, a pull-off stud also carried by the head and operating to draw off intermittently lengths of tape from a source of supply, and a take-up lever to deliver said tape to the tape-delivery means. 115

10. In a device of the class described, the combination with a work support over which work is fed, of tape-guiding means to deliver tape to the work, a movable head, a presser member carried by the head and acting intermittently on the tape to press it against the work, a pull-off stud carried by 125 the head and operating intermittently to 130

- draw lengths of tape from the source of supply, a driving shaft from which the head is operated, a take-up lever to deliver the lengths of tape from the stud to the 5 tape-guiding means, and means to actuate said take-up lever by said shaft.
11. In a device of the class described, the combination with a work support over which the work is fed, of means to apply 10 tape to the work, a reciprocating pull-off stud engaging the tape, means to reciprocate the stud thereby to intermittently pull off tape from a source of supply, means to deliver tape to the tape-applying means, and 15 a gripping device acting on the tape at the delivery side of the pull-off stud while the tape is being pulled off and on the opposite side of the stud while the tape is being delivered therefrom to the tape-applying 20 means.
12. In a device of the class described, the combination with a work support, of means to apply tape to the work as it is fed over said support, a reciprocating pull-off stud 25 engaging the tape, means to reciprocate said stud whereby on movement in one direction said stud draws off a length of tape from a source of supply and during the movement in the opposite direction gives up said 30 length, a take-up lever to deliver the tape from the stud as the latter gives it up, and a tape-gripping device operating to grip the tape on the delivery side of the stud while tape is being drawn from the 35 source of supply and on the opposite side of the stud while the take-up lever operates.
13. In a device of the class described, the combination with a work support, of means to lay tape on the work as it is fed over 40 said support, a reciprocating head, means to reciprocate it, a presser member carried by the head to apply intermittent pressure to the tape, and a pull-off stud carried by said head, a gripping device actuated by 45 the movement of the head and operating to grip the tape on the delivery side of the stud during its pulling-off movement and on the opposite side when the tape is delivered from the stud.
14. In a device of the class described, the combination with a work support, of means to lay tape on the work as it is fed over 50 said support, a reciprocating head, a presser member carried thereby and operating to apply pressure intermittently to the tape, a pull-off stud carried by the head and operating first to pull off a length of tape from a source of supply and then give up said length, a take-up lever to deliver 55 the tape from the stud and a gripping device to grip the tape on the delivery side of the stud during the pulling-off movement but on the opposite side of the stud while the take-up lever operates.
15. In a machine for applying tape to

sheet material, the combination with a work support over which the work is fed, of tape-applying means to lay on the work as it is fed a continuous length of tape extending in the direction in which the work is fed 70 and a pull-off device operating while the tape is being laid to draw tape from the source of supply and deliver it to the tape-applying means under a less tension than that to which the tape is subjected while 75 being pulled off from the source of supply.

16. In a device of the class described, the combination with a work support in the form of a roll, of means to lay tape on the work as it is fed over the roll, a presser 80 member having a face to engage the work, means to actuate the presser member thereby to cause said face to move toward and from the work and also to move in the direction in which the work is fed, said face 85 being so curved that it will have a rolling contact with the work during the forward movement thereof.

17. In a machine of the class described, the combination with a work support in the form of a roll, of means to lay tape on the work as it is fed over said roll, a combined presser and feed member having a concavely-curved face, means to move said member toward and from the work thereby 90 to press the tape against the work and also to oscillate said member so as to cause the curved face thereof to have a forward rocking motion while in contact with the work thereby to feed the work. 95

18. In a machine of the class described, the combination with a work support having a convexly-curved work supporting surface, of means to lay tape on the work as it is fed over said surface, a combined presser member and feed member having a concavely-curved face, means to move said member toward and from the work, thereby to press the tape against the work and also to oscillate said member so as to cause the concavely-curved face thereof to have a forward rocking motion while in contact with the work thereby to feed the work. 100 110

19. In a machine of the class described, the combination with a freely revolving work support having a continuous curved face, of means to lay tape on the work supported on said support, a presser member, means to move said member into engagement with the tape to press it against the work and then to move it forward to feed the work, the dimension of the face of said presser member which acts on the work being greater in the direction of the length of feed than each feeding movement whereby each portion of the tape is acted on a plurality of times by the presser member. 115 120

20. In a machine of the class described, the combination with a work support having a continuous curved work-supporting sur- 130

- face, of a tape-guiding member to deliver tape to the work, said member having side flanges between which the tape is received, a combined presser member and feed member, 5 means for oscillating said member by which it applies pressure intermittently to the tape and has a forward feeding movement while in engagement with the tape thereby to feed the work and a yielding tension foot 10 bearing on the tape between the flanges of the tape-guiding member, said tension foot being so constructed as to permit manual displacement for convenience in threading the machine.
- 15 21. In a machine of the class described, the combination with a work support, of means to apply tape to the work as it is fed over the work support, and means to cause the tape to gather on either edge at the will 20 of the operator as it is laid on a curved path preparatory to attachment to the work by adhesive contact.
22. In a machine of the class described, the combination with a work support, of 25 means to deliver tape to the work as it is fed thereover, a presser member acting intermittently on the work to press the tape thereagainst and feed the work forward, and a spring-pressed finger bearing on the tape 30 near one edge in front of the tape-delivery device and acting as a pivot about which the work may be swung between each feeding movement to cause the tape to follow a curved path.
- 35 23. In a machine of the class described, the combination with a work support over which the work is fed, of a tape-guiding device to deliver tape to the work, a presser member acting intermittently on the tape to 40 press it against the work, a pair of spring-pressed fingers engaging the tape near its
- edges and in front of the tape-delivery guide, each finger acting as a pivot about which the work may be swung when the presser member is raised thereby to lay the 45 tape in a curved path in either direction.
24. In a machine of the class described, the combination with a work support, of a tape-guide to deliver tapes to work as it is fed over the work support, a presser member 50 acting intermittently on the tape to press it against the work and means constituting a pivot about which the work can be turned when the presser member is elevated thereby to provide for laying the tape in a curved 55 path.
25. In a machine of the class described, the combination with a work support, of a tape-guiding member to deliver tape to the work support, means to press the tape 60 against the work and to feed the work forward, and means acting on the work at the marginal portion of the tape and constituting a pivot about which the work may be turned between feeding movement to lay the 65 tape in a curved path.
26. In a machine of the class described, the combination with a work support, of a guide to lay tape on the work, a presser member to press the tape against the work and 70 feed the work forward intermittently, two spring-pressed fingers acting on the work near the opposite edges of the tape, each finger acting as a pivot about which the work may be turned between feeding movements to enable the tape to be laid in a curved path, and means for rendering either finger inoperative.

In testimony whereof, I have signed my name to this specification.

WALTER P. OSGOOD.
